PAPER LINER FOR BOXES

William Wellington Moore, Vancouver, British Columbia, Canada

Application April 5, 1933, Serial No. 664,542

3 Claims. (Cl. 217—3)

My invention relates to improvements in paper liners for boxes, which are particularly adapted for use in lining boxes in which butter is compressed and packed.

5 In the packing of butter in boxes difficulty is experienced in so packing it that the flavour is not imparted to the butter from the wood used in the manufacturing of the box.

Mould is frequently manifested on the surface 10 of the butter from the seepage of water contents from the butter and fermentation due to extraneous bacterial conditions. I have discovered that this can be largely overcome if the butter can be kept from actual contact with the wood 15 and seepage of the water content is permitted to get away from the butter without forming direct communication with the wood. It is with a view to overcoming these difficulties that the present liner is designed, which consists essentially of a 20 liner comprising two strips of suitably treated paper laid one across the other over the bottom of the box and means are provided for the discharge of the moisture content of the butter and the retention of the butter from actual contact 25 with the box, as will be more fully described in the following specification and shown in the accompanying drawing, in which:—

Fig. 1 is a perspective view of a box fitted with the invention and showing one end of the box 30 removed.

Fig. 2 is a general view of the liner made in strip form from a continuous strip of paper.

In the drawing like characters of reference indicate corresponding parts in each figure.

35 In the preferred form of the invention I take a strip of paper generally indicated by the numeral 1 and pass it through a set of rolls where it is split longitudinally along the line indicated by the numeral 2 to divide it into two strips 3 and 4. The strips 3 and 4 will be creased along the transverse lines 5 and 6, and the strip is also transversely creased as at 7, longitudinal creases are formed as at 8 on the strip 3 and transverse lines of weakness or perforations are formed at 9, which lines are provided with small starting notches on each side of both strips as at 10, the reason for which is that the paper preferred is relatively heavy and a starting notch will greatly facilitate the severance of the strips at the desired 45 line.

At the intersection of the lines 5 and 8 a relatively large seepage perforation 11 preferably circular, is formed, which merges into a triangular perforation 12 extending towards the borders 55 of the strip 3, similar triangular perforations 12

are formed at the intersection of the lines 6 and 8.

Between the triangular perforations 12 and the border lines of the strip 3 webs 13 are formed, the purpose of which are to leave a continuous or unbroken edge at the sides of the strip. Further seepage perforations 14 are provided in spaced relation along the creases 5.

The paper of which these liners are made is preferably impregnated with a solution of wax or oils to render it impervious to moisture and 60 various forms of contamination, the preferred process being to form the creases as before described when the strips are passed through rollers and suitable folding devices, whereby the paper is well broken along the lines 8 to make 70 the strip fold with consummate ease and subsequently to form the perforations, when the paper will be passed into a bath of solution where it is impregnated and suitably pressed and dried and made up onto rolls of suitable size for delivery to the trade. 75

By providing the ends of the transverse creases with the webs 13, the strip can pass through the sundry rolls and any immersion or impregnation process can be adopted without causing the 80 borders 15 of the strip to fold back or become broken or torn adjacent the ends of the transverse creases 5 and 6.

The numeral 16 indicates generally a box having a bottom wall 17, side walls 18 and end walls 85 19 (one of which is omitted for the purpose of showing the liner).

In use a liner strip is severed from the roll by tearing it along the line of weakness 9 and is placed across the box and its centre section A 90 pressed downwards into contact with the bottom wall of the box. By virtue of the creases 5 and the seepage perforations 14, the strip will fold readily, so that the sections B will follow downwards and lie in contact with the side walls 18, with the pressing downwards of the section A the borders of the strip will automatically fold to lie against the end walls 19, with the webs 13 between the sections A and B folding over in the manner shown. When the strip is in position 100 with the sections A and B in the box, the free ends, or sections C are pressed outwardly breaking the webs 13 between the sections B and C and allowing said sections C to fall outwardly as shown and to fold again along the creases 7 towards the sides of the box as indicated by dotted lines in Figure 1. A strip 4 is then taken and placed transversely of the strip 3 and is handled in the same manner, pressing down the section D onto the section A, thus allowing the sections 105 110

E to contact with the end walls 19 and lie within the folded borders 15 of the strip 3.

It is invariably found that the lower edges of the block of butter forced into a box are rounded and do not therefore fit intimately into the angles around the bottom wall of the box, though a powerful ram is used to compress the butter, the interspace, though slight, between the edges of the butter and the angles of the bottom wall provides a suitable space for seepage to flow, which seepage escapes through the perforations 11 and 14 in the strip, these perforations, it should be noted, may be partially but not wholly covered by the strip 4. The rounding of the lower corner of the block of butter due to lack of localized pressure when filling prevents any extrusion of butter through the perforations 11, so that actual contact between the butter and the wood surfaces of the box is definitely precluded:

20 What I claim as my invention is:

1. A liner for butter boxes and the like comprising two strips of paper, one to entirely cover the two side walls, the bottom wall and the borders of the remaining side walls of the box and the other to entirely cover the remaining side and the bottom wall; said first strip having a plurality of relatively small seepage perforations at the intersection of the side and bottom walls adapted to be partially covered by the second named strip, said first named strip having apertures in close proximity to each side and within

the remaining side wall border covering portions to facilitate the folding of said portions at the corners of the box.

2. In a liner for butter boxes and the like consisting of two strips of paper adapted to be placed with one strip extending transversely of the other across the bottom wall of the box, one of said strips being creased longitudinally and transversely for folding and consisting of side and bottom sections and a border extending along both sides of said strip, said border having apertures at the intersection of transverse and longitudinal creases, one of the borders of said apertures serving to maintain the edges of the strip unbroken substantially as described. 80

3. In a liner for butter boxes and the like consisting of two strips of paper with one strip extending transversely of the other across the bottom wall of the box, one of said strips being creased longitudinally and transversely for folding and consisting of side and bottom sections and a border extending along both sides of said strip, said strip having apertures at the intersection of the longitudinal and transverse creases, and a narrow parallel-sided marginal portion to each aperture adjacent the side of the strip said portion serving to maintain the strip unbroken during manufacture and when being fitted into the box. 90
